(57) **CLAIM**

The ornamental design for a leaf and debris chute, as shown and described.

DESCRIPTION

FIG. 1 is a front side perspective view of a leaf and debris chute showing my new design;

FIG. 2 is a top plan view thereof;

FIG. 3 is a bottom plan thereof;

FIG. 4 is a left side elevational view thereof;

FIG. 5 is a right side elevational view thereof;

FIG. 6 is a rear side elevational view thereof; and,

FIG. 7 is a perspective view similar to that of FIG. 1, but including broken lines showing a trash bag in condition of use with my new design.

The front panel of the chute is shown broken away in FIG. 1 for convenience of illustration.

The broken line showing of a bag in FIG. 7 is included for the purpose of illustrating environment and forms no part of the claimed design.
